UNITED STATES PATENT OFFICE.

CHARLES WILLIAM WILSONE BROUN, OF RUGELEY, ENGLAND.

WIRE-STRAINER FOR FENCE-POSTS AND OTHER LIKE PURPOSES.

1,084,393.

Specification of Letters Patent.

Patented Jan. 13, 1914.

Application filed September 16, 1913. Serial No. 790,056.

To all whom it may concern:

Be it known that I, CHARLES WILLIAM WILSONE BROUN, a subject of His Majesty the King of England, residing at Levett 5 House, Rugeley, in the county of Stafford, Kingdom of England, land agent, have invented certain new and useful Improvements in Wire-Strainers for Fence-Posts and other like Purposes, of which the following 10 is a specification.

This invention relates to improvements in wire strainers or winders for fence posts and other like purposes, and it chiefly refers to the method of attaching them to the fence 15 posts especially those formed of reinforced concrete. In such devices as at present employed for wire fencing it is the common practice to pass the ends of the fence wires through corresponding holes in the fence 20 post on which the winders are provided and then to connect them to the winding arbor. As it is necessary that the several wires from 25 post to post should be in alinement with one another this arrangement results, with reinforced work specially, in the usual expensive practice of providing two winding posts adjacent to each other at the required intervals in order to strain the wires in both 30 directions, and in order to equalize the strain on the posts they are usually braced together by a straining bolt or band.

Now according to my present invention I provide a straining device, which although it is mounted on a post, virtually forms an integral 35 part of the wire, which can therefore be connected to the device on each side of the post in correct alinement. Also I am enabled to dispense with the use of two posts and two sets of straining devices as the post 40 will be kept vertical by the fence wires which are connected to it from each side.

In order that my invention may be more clearly understood I will hereinafter describe the same with reference to the accompanying 45 drawings in which:

Figure 1 is a detail side elevation showing my invention applied to a fence post; Fig. 2 is a sectional plan view thereof; Fig. 3 is a reverse side view of the straining device or 50 winder proper; and Figs. 4, 5 and 6 are similar views respectively illustrating a modified arrangement.

As shown, the winder or straining device proper comprises preferably a metal U-shape 55 frame *a* of channel shape in which the wind-

ing arbor *b*, to which the end of the wire *c* is attached, is suitably journaled. The arbor *b* is squared at one end as shown at *d* for enabling it to be rotated and at its other end it is provided with a ratchet wheel *e* 60 which is engaged by a resilient pawl or catch *f* the end of which is fastened in any suitable manner on the frame *a* to prevent backward rotation of the arbor when the wire *c* has been tightened. Such a device *per se* 65 is not novel and no broad claim is made to its construction.

The winder is secured to one face of the post *g* by means of a bolt *h* which passes through a hole therein. At one end just 70 under its head *h*¹ the bolt *h* is of angular or square section as shown at *h*² and this angular portion is adapted to engage a correspondingly shaped hole *a*¹ in the plate *a* for the purpose of preventing its rotation 75 when the bolt is tightened in position. The said bolt *h* is threaded at its other end and after being passed through the post *g* it is held in place by means of an eye-nut *k* which is adapted to be tightened up against a suitably shaped washer *l* and also to form a loop 80 for connection with the end of the wire *c*¹ on the opposite side of the post.

If desired I might, as in Figs. 4, 5 and 6 of the drawings employ other fastening means in place of the eye nut *k* for holding the winder in position, for instance I might employ an ordinary eye-bolt *h* and nut *h* the eye-bolt *h* being threaded throughout its length and screwing into a tapped hole *a*¹ 90 in the winder *a* or I might provide an additional swivel or other fastening device for connecting with the end of the wire *c*¹. Or if desired the wire *c*¹ could be passed directly through a transverse perforation 95 formed in the end of the bolt *h* which could then be arranged as preferred as in Figs. 1, 2 and 3 or as in Figs. 4, 5 and 6.

Thus it will be appreciated that by my invention the bolt *h* which passes through the 100 post *g* forms the only fastening means for the strainer *a* and in effect forms an integral portion of the wire *c* *c*¹ which by my invention passes away from opposite sides of a single post.

I claim—

1. In combination, a wire stretcher or winder for fence posts, a bolt, said bolt adapted to pass through a post to secure 110 said stretcher to the post, and means on the

free end of the bolt to connect a wire on the opposite side of said post for the purpose described.

2. In combination, a stretcher or winder for fence posts, and a bolt having an eye at its free end, said bolt adapted to pass through a post to secure said stretcher to the post.

3. In combination, a wire stretcher including a U-shape frame formed with an opening, a bolt fitting in the opening and adapted to pass through a post to secure said

stretcher to the post, an element on the bolt to engage the opposite side of the post to form a clamp, and means on the bolt to secure a wire on the opposite side of the post. 15

In testimony whereof I have hereunto signed this specification in the presence of two subscribing witnesses.

CHARLES WILLIAM WILSONE BROUN.
